AIR DISTRIBUTING VALVES

Donald G. Phinney, St. Louis, Mo., assignor to The McNeil Machine & Engineering Company, Akron, Ohio, a corporation of Ohio

Filed July 24, 1959, Ser. No. 829,363

10 Claims. (Cl. 121—46.5)

This invention relates to air distributing valves, and more particularly to anti-icing means for the distributing valve of an expandable-chamber air motor.

The invention involves an improvement upon the air distributing valve of an air motor of the type such as shown in Klein United States Patent 2,750,932 comprising a cylinder, a piston working in the cylinder, and valve means including a slideable main distributing valve member having a cavity therein for controlling the supply of air to and the exhaust of air from the opposite ends of the cylinder. A problem which has been encountered in the operation of such air motors, particularly as regards larger capacity motors, is the formation of ice in the cavity of the slideable main distributing valve member which may at times be serious enough to block flow through the cavity. Ice may form, particularly when the air is humid, because of the cooling effect of the expansion of air in the cavity.

Accordingly, among the several objects of this invention may be noted the provision of means for effectively preventing the accumulation of ice in the cavity of the slideable main distributing valve member; and the provision of such anti-icing means which does not interfere with the action of the valve member, and which is economical to manufacture and install. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

Fig. 1 is a longitudinal section of an air motor having a distributing valve provided with anti-icing means of this invention;

Fig. 2 is an enlarged fragment of Fig. 1 with parts further broken away and shown in section;

Figs. 3 and 4 are enlarged transverse sections taken on lines 3—3 and 4—4, respectively, of Fig. 1;

Fig. 5 is a longitudinal section taken on line 5—5 of Fig. 3; and,

Fig. 6 is a perspective of a reed which is incorporated in the distributing valve in accordance with this invention.

Corresponding reference characters indicate corresponding parts throughout the several views of the drawings.

Referring to the drawings, there is indicated at 1 an expandable-chamber air motor provided with anti-icing means of this invention. Essentially, the motor comprises a cylinder 3 (shown in vertical position in Fig. 1) having upper and lower end heads 7 and 9. A piston 11 reciprocates in the cylinder. The piston is fixed on the upper end of a piston rod 13 which extends through the lower head. A valve seat block 15 extends lengthwise on the outside of the cylinder between the end

2

heads. This block has a flat outer face 17, feed passages 19 and 21 and an exhaust passage 23. The latter is formed by a hole 25 extending transversely completely across the block located centrally of the length of the block and by an entrance hole 27 bored in from the outer face 17 of the block to an intersection with hole 25. The feed passage 19 is formed by a longitudinal hole 29 bored in from the upper end of the block to a point short of the hole 25 and by a hole 31 bored in from the face 17 of the block to an intersection with the lower end of hole 29. The feed passage 21 is formed by a longitudinal hole 33 bored in from the lower end of the block to a point short of the hole 25 and by a hole 35 bored in from the face 17 of the block to an intersection with the upper end of hole 33. Holes 29 and 33 open into passages 37 and 39 in the upper and lower end heads 7 and 9, respectively.

A valve seat face plate 41 is secured on face 17 of block 15. A valve chest 43 is secured to block 15 over this plate. This chest has upper and lower longitudinal cylindrical bores 45 and 47 open to an enlarged central pressure chamber 49. Compressed air for driving the motor is delivered to chamber 49 through an air inlet 51. A valve-actuating piston 55 is adapted for lengthwise reciprocation in the valve chest 43, the ends of the piston being slideable in the bores 45 and 47. Valve gear for operating the piston 55 from the motor piston 11 is indicated at 71. This is essentially the same as that shown in the aforesaid United States Patent 2,750,932 and reference may be made thereto for full details.

As in the motor shown in United States Patent 2,750,932 piston 55 controls a main distributing slide valve member 87 and an auxiliary distributing slide valve member 89. The main valve member 87 is a D-valve slideable on valve seat plate 41. It controls the supply and exhaust of air to and from the opposite ends of motor cylinder 3. The auxiliary valve member 89 is also a D-valve slideable on valve seat plate 41 at one side of main D-valve member 87. It controls the supply and exhaust of air to and from the outer ends of bores 45 and 47 in valve chest 43. On valve seat plate 41 is secured a plate 90 having an opening 91 therein which serves as a guide and end stop for the two slide valve members. The main D-valve member 87, as shown, is relatively short and wide as compared to the auxiliary D-valve member 89, the latter being relatively long and narrow. The opening 91 is shaped somewhat like a T, as shown in United States Patent 2,750,932, having a relatively short wide portion accommodating the sliding of the main D-valve member 87 and a longer narrow portion accommodating the sliding of the auxiliary D-valve member 89. The two D-valve members are guided by the sides of the opening 91. The piston 55 has a notch 97 corresponding in length to the length of the auxiliary D-valve member 89. This notch receives the shorter main D-valve member 87 with lost-motion (see Fig. 1). Engagement of the ends of the auxiliary D-valve member 89 with the ends of opening 91 determines the limiting end positions of the piston 55.

In the line of motion of the main D-valve member 87, the valve seat plate 41 has a main central exhaust port 99 aligned with the hole 27 of exhaust passage 23 in the block 15, a main feed port 101 above port 99 aligned with the hole 31 of feed passage 19 and a main feed port 103 below port 99 aligned with the hole 35 of feed passage 21. The porting arrangement for the supply and exhaust of air to and from the outer ends of bores 45 and 47 under control of the auxiliary D-valve member 89 is essentially the same as that shown in United States

Patent 2,750,932. Reference may be made to said patent for full details.

In accordance with this invention, the cavity 129 in the main D-valve member 87 is of arcuate form lengthwise of the valve member, concave as regards the inside face of the valve member. The surface of the cavity 129 is preferably coated as indicated at C with a material which tends to prevent ice from adhering thereto, such as a silicone resin, or polymerized tetrafluoroethylene (sold under the trade name Teflon). A similar coating C may be used in the cavity of the auxiliary D-valve 89, also in the various ports and passages as shown. The valve seat block 15 is provided with a hole 131 in the bottom thereof extending up to the transverse exhaust passage hole 25 and in line with exhaust passage hole 27 in the block and with the main central exhaust port 99 in the valve plate 41. This hole 131 is counterbored at its bottom end (its end toward the cylinder 3) as indicated at 133. This provides a relatively thin annular rim 135 at the other end of the hole.

A plug 137 made of elastomeric material, preferably a synthetic rubber such as that sold under the trade name neoprene, is secured to the block 15 under compression in the hole 131. For this purpose, the plug has a circular base portion 139 provided with an annular groove 141 which receives the rim 135. The plug also has an integral stem portion 143 extending from the base portion 139 into the transverse exhaust hole 25 in the block toward and in line with the exhaust hole 27 in the block and the main central exhaust port 99 in the valve plate 41. The stem portion 143 is molded around a flat reed 145, which may be made of Phosphor bronze spring strip material having a width somewhat less than the width of the cavity 129 in the main D-valve 87. The reed 145 is shown as having a hole 147 therein which is filled with rubber during the molding of the plug to hold the reed in assembly with the plug. The reed is of such length as to extend through the hole 27 and port 99 and beyond valve plate 41 into the cavity 129 in the main D-valve 87. The plug 137 is turned so that the plane of the reed is transverse to the length of the main D-valve. The reed normally is perpendicular to the plate 41, and, when perpendicular, projects beyond the face of the plate 41 a distance approximately half the maximum depth of the cavity 129 in the main D-valve (see Figs. 1 and 2). Notches such as indicated at 149 in Fig. 6 are provided at the lower end of the plug for receiving keys such as indicated at 150 at opposite sides of hole 133 to hold the assembly of the plug and reed from rotating out of proper position.

It will be understood that the main D-valve member 87 is slidable back and forth on valve seat plate 41 between a first position wherein the cavity 129 in the D-valve member 87 provides for communication from a first feed port (port 103 as shown in Figs. 1 and 2) to the exhaust port 99 and a second position wherein the cavity provides for communication from the second feed port (101) to the exhaust 99. In the first position of D-valve member 87, air is supplied from the chamber 49 to the upper end of the cylinder 3 via feed port 101 and feed passages 19 and 37, and exhausted from the lower end of the cylinder via feed passages 39 and 21, port 103 and cavity 129. In the second position of the D-valve member 87, air is supplied from the chamber 49 to the lower end of the cylinder 3 via feed port 103, and exhausted from the upper end of the cylinder via passages 37 and 19, port 101 and cavity 129.

Expansion of air in cavity 129 tends to cause cooling of the air and freezing of moisture in the air in the cavity, but reed 145, which is oscillable in the exhaust port 99 in the line of movement of the D-valve member 87, prevents accumulation of ice in the cavity, aided by the coating C. Reed 145 also prevents icing in port 99 and holes 27 and 25, as may occur without the reed. The exact manner in which the reed prevents the accumula-

tion of ice is not precisely understood at present, but it acts most effectively for this purpose, without interfering with the flow of air. The tendency toward icing in the cavity of the auxiliary D-valve 89 is much less than the tendency toward icing in the cavity of the main D-valve 87. Hence, it is not necessary to provide a reed for the auxiliary D-valve.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. In an air distributing valve comprising a valve seat having an exhaust port between first and second feed ports, and a valve member having a cavity therein slidable back and forth between a first position wherein the cavity provides for communication from the first feed port to the exhaust port and a second position wherein the cavity provides for communication from the second feed port to the exhaust port, expansion of air in said cavity tending to cause cooling of the air and freezing of moisture in the air in the cavity; means for preventing accumulation of ice in the cavity comprising a reed carried by said seat within said exhaust port and projecting out of said exhaust port into said cavity, said reed being oscillable in said exhaust port in the line of movement of the slidable valve member.
2. In an air distributing valve as set forth in claim 1, said cavity being of arcuate form lengthwise of said slidable member and having a coating of material resistant to adherence of ice.
3. In an air distributing valve as set forth in claim 2, said reed projecting into said arcuate cavity a distance less than the maximum depth of said arcuate cavity.
4. In an air distributing valve as set forth in claim 1, said reed comprising a length of spring strip material.
5. In an air distributing valve as set forth in claim 4, said reed having an end portion embedded in a base of elastomeric material, said base being secured in a hole in said valve seat.
6. In an air distributing valve for an air motor, said motor comprising a cylinder and a piston movable in the cylinder, said valve comprising a block extending lengthwise of the cylinder on the outside thereof, a plate on the outer face of the block constituting a valve seat, a valve chest overlying said plate, said block having an exhaust passage including a transverse hole and an entrance hole extending from the outer face of the block to said transverse hole, said block also having feed passages in communication with the ends of the cylinder, said plate having an exhaust port in communication with said entrance hole in the block and first and second feed ports on opposite sides of the exhaust port in communication with the feed passages in the block, a D-valve member having a cavity therein slidable back and forth on said plate between a first position wherein the cavity provides for communication from the first feed port to the exhaust port and a second position wherein the cavity provides for communication from the second feed port to the exhaust port, expansion of air in the cavity tending to cause cooling of the air and freezing of moisture in the air therein; means for preventing accumulation of ice in the cavity comprising a reed attached to the block extending through said entrance hole in the block and said exhaust port in said plate and projecting into said cavity in the D-valve member, said reed being oscillable in said entrance hole and said exhaust port in the line of movement of said D-valve member.
7. In an air distributing valve as set forth in claim 6, said cavity being of arcuate form lengthwise of said

D-valve member and having a coating of material resistant to adherence of ice.

8. In an air distributing valve as set forth in claim 7, said reed projecting into said arcuate cavity a distance less than the maximum depth of said arcuate cavity.

9. In an air distributing valve as set forth in claim 6, said reed comprising a length of spring strip material.

10. In an air distributing valve as set forth in claim 9,

said reed having an end portion embedded in a base of elastomeric material, said base being secured in a hole in the bottom of the block.
